(57) **CLAIM**

The ornamental design for a gun bag, as shown and described.

DESCRIPTION

FIG. 1 is a perspective view of the gun bag in a backpack position, showing our new design;

FIG. 2 is a left view of the gun bag in a handbag configuration;

FIG. 3 is a right view thereof;

FIG. 4 is a back view thereof;

FIG. 5 is another back view thereof;

FIG. 6 is a front view thereof;

FIG. 7 is a top view thereof; and,

FIG. 8 is a bottom view thereof.

The broken lines in the drawing represent stitching that does not form part of the claimed design.
